VENDING MACHINE

Charles J. Warren, Los Angeles, Calif., assignor
to Theodore A. Woolsey, Pasadena, Calif.

Application October 6, 1945, Serial No. 620,805

11 Claims. (Cl. 225—21)

1 This invention relates to check-controlled vending apparatus of the general character embodied in my United States Letters Patent No. 2,370,276, issued February 27, 1945, which discloses and claims a machine for dispensing, under the control of a coin, any and all fluid substances including liquids such as fruit juices, milk, carbonated liquids, or other beverages.

The machine of the above identified patent discloses means to place a cup and dispense a predetermined quantity of liquid thereinto in response to the deposit of a coin into the machine; to deliver a cup to liquid-receiving position wherein the cup is accessible for manual removal upon dispensing the liquid into the cup; to maintain the supply of liquid in a cooled state for preservation and palatable consumption; to guard against tampering with or clogging the liquid discharging mechanism; to insure filling of a cup with a predetermined quantity of the liquid before permitting removal of the cup by the customer; to guard against injury of persons incident to tampering with the machine; to render the machine sanitary at the liquid-dispensing station of the machine; to enable several cups of liquid to be dispensed in rapid succession in response to the deposit of a like number of coins; and to provide a machine which is attractive and inviting in appearance, is sanitary, self-contained, and retains wasted or spilled liquid, as well as being particularly adapted for use at locations requiring neatness of the machine and the area about same.

It is an object of the present invention to provide a check-controlled vending machine for any and all fluid materials, which is structurally characterized by means having all of the functional advantages of the patented machine above identified, and which in addition, accomplishes the operations of placing the cup in position to receive liquid, discharging the predetermined quantity of liquid into the cup, and delivering the filled cup to the customer, by the use of a lesser number of simply constructed parts whose functioning is absolutely positive, dependable, accurate and trouble-free to reduce inspection, maintenance and repair costs to a negligible minimum, as well as materially reduce the cost of the machine so as to place the machine within the financial reach of the greatest possible number of prospective users.

It is another object of the present invention to provide a vending machine of the above described character whose mechanism for moving a cup from a supply thereof to the filling position, and for delivering the filled cup to the customer

for manual removal, includes a rotary carrier which is structurally characterized and associated with the machine in a manner for the cup-filling operation to take place within the sanitary interior of the machine, with the liquid dispensing faucet or outlet being inaccessible from exteriorly of the machine so as to be fully protected against contamination by flies and other insects and foreign matter in the atmosphere, as well as rendering the cup inaccessible to the customer until the filling operation has been completed, to thus positively prevent premature removal of a cup from the carrier during the filling operation, with the attending discharge and waste of liquid onto the carrier.

It is a further object of the present invention to provide a rotary cup carrier and actuating and locking mechanism therefor which are absolutely positive and accurate in operation to deliver a single cup to the customer in response to each coin deposited into the machine, and which is adequately protected against becoming jammed by a cup inadvertently or carelessly replaced on the carrier after having been used by the customer, whereby to obviate loss of revenue from inoperativeness of the machine by jammed mechanism, and the attending annoyance to a customer upon being unable to use the machine.

It is a still further object of the present invention to provide a liquid vending machine having a storage receptacle of relatively large capacity in which a pre-carbonated beverage, for example, can be initially charged with a sufficiently high pressure to insure that the entire contents of the receptacle will be elevated automatically as required to replenish the supply of liquid in a relatively small capacity refrigerated dispensing tank, in which latter a predetermined low pressure sufficient to prevent loss of carbonation is maintained, with the liquid being maintained at a predetermined level in the dispensing tank irrespective of the withdrawal of liquid therefrom, in order that the hydrostatic pressure for the gravity flow of liquid from the dispensing tank to a valve-controlled dispensing outlet, will remain the same, to insure the delivery of a measured quantity of liquid to a cup at each operation of the machine.

With these and other objects in view, the invention resides in the combinations, arrangements and functional relationships of elements as set forth in the following specification and particularly pointed out in the appended claims.

In the accompanying drawings:

Figure 1 is a view showing in front elevation,

one form of vending machine embodying this invention;

Figure 2 is an enlarged vertical front view with the cabinet or casing of the machine in section to expose the mechanism and units of the invention in elevation;

Figure 3 is an enlarged fragmentary horizontal sectional view taken on the line 3—3 of Figure 2;

Figure 4 is a fragmentary perspective view of actuating mechanism for the cup carrier embodied in the invention;

Figure 5 is a fragmentary horizontal sectional view taken on the line 5—5 of Figure 2;

Figure 6 is a view in front elevation of the cup carrier shown in Figure 5;

Figure 7 is a horizontal sectional view taken on the line 7—7 of Figure 2, and illustrating the normal locked position of the cup carrier;

Figure 8 is a fragmentary vertical sectional view taken on the line 8—8 of Figure 7;

Figure 9 is a view similar to Figure 7 and illustrating the cup carrier unlocked for movement by its actuating mechanism;

Figure 10 is a vertical sectional view of the dispensing tank for carbonated liquids, embodied in the invention, and

Figure 11 is a horizontal sectional view taken on the line 11—11 of Figure 10.

Referring specifically to the drawings, the invention in its illustrated embodiment is composed of a relatively tall and narrow rectangular cabinet 15 of metal, providing a base 16, back wall 17, side walls 18 and a front door 19 mounted on a vertical hinge 20, and extending from the base to the open top of the cabinet which is closed by a hinged cover 21, the door 19 and the cover 21 being locked together by a single lock 22.

Supported on the base 16 beneath a horizontal partition 23 is a removable receptacle 24 of relatively large capacity in which is stored under pressure a carbonated beverage to be dispensed. A discharge pipe 25 extends vertically downward through the neck of the receptacle to a point close to the bottom of the latter, and is controlled by a regulating valve 26 in the neck of the receptacle as shown in Figure 2. The original pressure in the receptacle 24 may be as high as 240#/sq. in., and, in any event, must be sufficiently high to elevate the entire contents of the receptacle as required, to an insulated dispensing tank 27 supported in the upper portion of the cabinet 15 as shown in Figure 2.

The beverage in the dispensing tank 27 is automatically maintained in a cooled state suitable for preservation and palatable drinking, by a conventional type of thermostatically controlled refrigerating unit 28 whose refrigerating coils 29 are horizontally disposed in the tank 27 and are included in the usual fluid circuit of the unit as is well known in the art.

The bottom of the dispensing tank 27 is provided with an outlet 30 connected to a valve which may be in the form of a faucet 31 whose spout 32 is disposed above a cup carrier designated generally at C and including a turntable 33 fixed to a vertical shaft 34 journaled in a bearing plate 35 resting upon and fixed to spaced, upstanding lugs 36 on a base plate 37 secured to the partition 23, all to mount the carrier C for rotation about a vertical axis.

The carrier C also includes a plurality of vertical partition walls 38 of which three are shown in the present instance equally spaced 120 degrees of angular distance apart, and radiating from the center of the turntable 33 as shown in Figures

5 and 6, to divide the area of the turntable into three separate segments. The walls 38 rise from the turntable to a height exceeding that of the cups which are adapted to be deposited onto the turntable from the magazine 40 of a conventional form of paper cup dispenser 41 having suitable well known mechanism including a spring-urged releasing lever 42 which, when actuated, effects the release of the lowermost cup in the magazine, for the deposit of the released cup in an upright position on the turntable 33 between two adjacent walls 38 thereof.

For an angular distance of 240 degrees, an arcuate guard wall 45 of a height corresponding to that of the walls 38, confines cups on the turntable against lateral displacement therefrom, with the remaining 120 degrees at the front of the turntable being unobstructed and open through the front door of the machine by the provision of a delivery opening 46 in the latter. The sides and top of the opening 46 co-act with the shelf-forming bottom 47 of the opening at the level of the turntable, to define a recess in the door at a height convenient for a customer to remove a filled cup from the turntable.

The guard wall 45 is supported by a tray 50 fixed to the bearing plate 35 and adapted to receive any spilled liquid which is free to drain from the turntable through openings 51 in the latter. The tray 50 is provided with an outlet spout 52 disposed to discharge the drained liquid into a removable container 53 suitably supported in the cabinet 15. A shutter-controlled opening 54 in the door 19 is provided for the deposit of used cups into the container 53 so as to enable the area surrounding the machine to be kept neat and clean.

In the normal locked position of the carrier C shown in Figure 3, which corresponds to the position of the actuating mechanism for the carrier designated generally at A in Figure 7, the cup dispenser 41 is disposed to deposit a cup onto one segment of the turntable 33 which constitutes a cup loading station S; the faucet 31 is disposed to discharge liquid into a cup on the segment of the turntable 120 degrees in advance in a clockwise direction as viewed in Figure 3, which constitutes a cup filling station S1; whereas the remaining 120 degree segment of the turntable which registers with the delivery opening in the front door 19, constitutes a cup delivering station S2.

For each insertion of a coin into a coin slot 60 in the front of the cabinet 15, a cup from the magazine 40 is caused to be deposited onto the turntable 33, and a cup previously deposited on the turntable caused to be filled with a predetermined quantity of liquid from the tank 27 and advanced from the filling station S1 to the delivering station S2 for removal by the customer.

For this purpose a shaft 61 is journaled in suitable bearings 62 and 63 on one side wall 18 and in the casing of a conventional reduction gearing train 64 driven by an electric motor 65, to which current is supplied by a suitable coin-controlled switch until the shaft has been driven through exactly one revolution, at which the motor circuit is opened, all automatically by mechanism forming no part, per se, of the present invention, and fully described in my Patent No. 2,370,276 above referred to.

Fixed to the shaft 61 is a cam 70 disposed to engage and actuate the cup release lever 42 of the cup dispenser 41 to deposit a cup onto the turntable 33 at the cup loading station S dur-

ing a portion of a revolution of the shaft. A second cam 71 is fixed to the shaft 61 and is engaged by a roller 72 on a rocker arm 73 mounted on a fixed pivot 74 on a bracket 75 secured to one side wall 18 of the cabinet 15. A spring 76 urges the arm 73 in a direction to maintain the roller 72 in engagement with the cam 71, and the arm 73 is operatively connected to the handle 77 of the valve of the faucet 31 by a link 78, all to positively open the faucet during a predetermined portion of a revolution of the shaft 61, and to close the faucet during the remainder of the revolution.

A third cam 80 is fixed to the shaft 61 and is received in a fork 81 formed at one end of a rocker arm 82 pivoted intermediate its ends at 83 on a bracket 84 secured to the side wall 18 and pivotally connected at its other end by a pin and slot connection 85 to one end of an actuating member 86 in the form of a flat bar mounted in brackets 87 on the base plate 37 for horizontal reciprocating movement.

Pivottally mounted at 90 on the member 86 is a pawl 91 urged in one direction by a spring 92. In the normal locked position of the turntable 33 shown in Figure 7, the pawl 91 engages a fixed cam 93 having a rounded nose 94 and supported on the plate 37 in the path of movement of the pawl by the bar 86, the pawl having been raised to a non-driving or releasing position by the cam, against the biasing action of the spring 92.

Pivottally mounted at 95 on the plate 37, and normally urged to locking position by a spring 96, is a locking element or dog 97 having a locking lug 98 adapted to enter any one of three equally spaced locking recesses 99 formed in the periphery of a locking disk 100 fixed to the shaft 34 so as to lock the turntable 33 against rotation. Projecting laterally from the actuating member 86 is an unlocking pin 101 disposed to engage a shoulder 102 on the locking element 97 during movement of the actuating member in one direction, and to move the locking element to the unlocking position shown in Figure 9 wherein the locking lug 98 has been moved out of a recess 99 in the locking disk 100, so as to free the same and hence the carrier C for movement by the pawl 91 in response to movement of the actuating member 86 in the reverse direction.

For this purpose the locking disk 100 is provided with pins 103, one for each recess 99 and equally spaced circumferentially in positions for one of the pins to always be disposed in the path of movement of the pawl by the actuating member in the aforesaid reverse direction, for engagement by the bill 104 of the pawl which effects a 120 degree rotational movement of the carrier C in a clockwise direction in synchronism with the cup-loading and filling during a single revolution of the shaft 61, as will be later fully described.

Fixed to the plate 37 by screws 105 is an arm 106 which constitutes a camming stop and is disposed horizontally a short distance above the top of the turntable 33 to project across the latter. The walls 38 of the carrier are each provided with a horizontal slot 107 at the level of the arm 106 to permit the walls to pass the arm during rotation of the carrier. Each of the walls 38 is provided on its leading side and at a higher level than the arm 106, with a vertically extending camming projection 108 adapted to co-act with the arm 106 in response to rotation of the carrier, to discharge therefrom, any cup left on or replaced on the turntable after the cup has been used, all to obviate possible jamming of the ma-

chine, as will be later fully described in the operation of the machine.

It will be noted that the liquid under relatively high pressure in the storage receptacle 24, is conducted to the dispensing tank 27 through a pipe 111 having a separable coupling 112 to permit convenient replacement of an emptied receptacle with a filled one to replenish the supply of liquid in the machine. The upper end of the pipe 111 is provided with a control valve 113, and is connected to a junction fitting 114 at the bottom of the dispensing tank 27, to which fitting is also connected the feed and return lines 115 and 116 of the refrigerating coils 29.

Supported vertically from the fitting 114 in communication with the pipe 111 is an inlet tube 117 which extends upwardly into the tank 27 to a point just below a horizontal partition 118 which divides the interior of the tank into a lower beverage chamber 119 and an upper, pressure or gas chamber 120. The partition 118 has a relatively large port 121 formed to provide a valve seat, and adapted to be controlled by a relief valve 122 urged to close the port by a spring 123, the loading of which can be varied by an adjusting screw 124 threadedly mounted in the top of the tank. A spring-loaded outwardly opening check valve 125 is also mounted in the top of the tank in communication with the chamber 120 to predetermine the maximum pressure therein as will be later fully described.

The upper end of the inlet tube 117 is provided with a head 126 having an inlet port 127 controlled by a disk valve 128 with which is operatively associated a float 129 in the form of a double convex, hollow, air-tight body having an axial opening therethrough freely receiving the inlet tube 117 to slidably mount the float thereon for rising and lowering movements by liquid in the beverage chamber 119. At equally spaced intervals circumferentially, actuating levers 131 are pivoted intermediate their ends at 132 on the head 126 to provide long arms 133 whose outer ends bear against the top surface of the float 129 adjacent its periphery, and short arms 134 bearing against the top surface of the valve 128 for co-action therewith in controlling the flow of beverage into the chamber 119 in the operation of the invention which is as follows:

Let it be assumed that the carrier C is locked in the position shown in Figures 3, 5 and 7, and that by hand or otherwise, cup a has been placed on the turntable 33 in the compartment thereof at the cup filling station S1 as shown in Figure 3. Let it also be assumed that a receptacle 24 containing the beverage to be dispensed, is connected to the dispensing tank 27, and that the float 129 has co-acted with the levers 131 to close the valve 128, thus predetermining the level at which the liquid will stand in the dispensing tank. It will be noted that the loading of the spring 123 is such that it will remain closed to maintain a maximum pressure of about 4# sq. in. in the beverage chamber 119, or a pressure at least sufficient to maintain carbonation of the liquid in such chamber, and that the valve 122 will open in opposition to the spring 123 should the pressure in the beverage chamber exceed this predetermined pressure, so as to vent the excess pressure into the chamber 120, whereby to insure that a uniform pressure will be constantly maintained in the beverage chamber irrespective of the gradual lowering of the superior high pressure originally provided in the receptacle 24.

Should the spring 123 fail or get out of adjustment, sufficient pressure, say about 3#/sq. in., will be maintained in the pressure chamber 120 by the loading of the spring of the check valve 125, to insure that carbonation of the beverage in the chamber 119 will be maintained with but a slightly lowered pressure which will have only a negligible effect on the quantity of beverage dispensed from the chamber 119 during the cup filling operation.

Upon the deposit of a coin into the slot 60, current is supplied to the motor 65 to rotate the shaft 61 in a counterclockwise direction as viewed in Figures 2 and 4, through exactly one revolution, under the control of the mechanism (not shown) fully disclosed in my Patent No. 2,370,276. During the initial portion of this one revolution of the shaft 61, the cam 71 co-acts with the roller 72, rocker arm 73 and link 78, to open the faucet 31, during which the cam 70 actuates the cup release lever 42 of the cup dispenser 41 to drop a cup in the compartment of the turntable 33 at the cup loading station S, as indicated at b in Figure 3.

As the cam 71 recedes from the roller 72, the spring 76 co-acts with the arm 73 and link 78 to close the faucet 31, it being understood that the timing of the mechanism is such that the faucet 31 will be open only so long as to dispense the exact amount of beverage from the uniformly pressured supply in the chamber 119, to fill the cup a to a predetermined level. As beverage discharges from the chamber 119 with the attending lowering of the float 129, the valve 128 will open sufficiently to replenish the quantity of beverage dispensed, so as to maintain the predetermined uniform level of beverage in the chamber 119.

During the filling operation, the cam 80 is co-acting with the rocker arm 82 to advance the actuating bar 86 to the right as viewed in Figure 7 until the pin 101 engages and moves the locking dog 97 to the unlocking position shown in Figure 9, at the completion of the filling operation.

In the unlocked position of the dog 97 as shown in Figure 9, the pawl 91 has just ridden over one of the pins 103 on the locking disk 100, and the bill 104 of the pawl is disposed to engage such pin as the return movement of the actuating bar 86 to the left as viewed in this figure, is now initiated, so as to rotate the carrier C in the clockwise direction as viewed in Figures 3, 5 and 7. The dog 97 is now freed of the pin 101 so that the spring 96 will urge the lug 98 of the dog into engagement with the periphery of the locking disk 100, for reentry into the next succeeding one of the recesses 99 when 120 degrees of movement of the carrier has been completed to dispose the compartment of the carrier containing the filled cup a at the delivery station S2, for removal by the customer.

The rounded nose 94 of the cam 93 is engaged by the bill 104 of the pawl 91 so as to raise the latter against the action of the spring 92, clear of that pin 103 being driven by the pawl, thus operatively disconnecting the pawl from the carrier C, and sufficiently prior to completion of 120 degrees of movement thereof for the inertia of the carrier to be compensated for, and relocking of the carrier by the dog 97 insured.

Should the cup a after use, be inadvertently or carelessly replaced on the carrier C instead of being dropped into the waste container 53 through the opening 54, or otherwise disposed

of, the stop 106 and the projection 108 on the carrier wall 38 immediately following this cup, will co-act by a circumferential wiping action upon the cup, to roll same from the carrier during the next operation of the machine, so as to positively prevent jamming or defective operation of the machine by such cup.

From the foregoing description, it will be manifest that during each cycle of operation of the machine, an empty cup will be deposited on the carrier C concurrently with filling of a previously deposited cup with a predetermined quantity of liquid or other fluid material from a supply thereof, all within the sanitary interior of the machine, and that following the filling operation, the normally locked carrier will be unlocked for a sufficient interval for the filled cup to be delivered to a delivery station exteriorly of the machine for removal from the carrier by the customer.

I claim:

1. In a vending machine, a cabinet having a delivery opening; a carrier mounted in the cabinet for rotation about a vertical axis and having vertical walls dividing the carrier circumferentially into a plurality of compartments; means locking the carrier against rotation with one of its compartments exposed in said delivery opening; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a cup previously deposited into a second compartment of the carrier in advance of said one compartment and within the cabinet; means for unlocking said carrier following the liquid discharging operation; means for imparting sufficient rotational movement to the carrier upon unlocking same, for the compartment thereof carrying the filled cup, to be exposed in said delivery opening, and for a third compartment of the carrier to be disposed to receive a cup from the cup dispensing mechanism while the last deposited cup has been advanced by the carrier to a liquid-receiving position with respect to the liquid dispensing mechanism; means for relocking the carrier following its aforestated movement; and co-acting means on the carrier and at the delivery opening, operable in response to said aforestated movement, to move from the exposed compartment of the carrier, any previously used cup replaced thereon, so as to prevent jamming of the carrier by such cup.

2. In a vending machine, a cabinet having a delivery opening; a carrier mounted in the cabinet for rotation about a vertical axis and having vertical walls dividing the carrier circumferentially into a plurality of compartments; means locking the carrier against rotation with one of its compartments exposed in said delivery opening; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a cup previously deposited into a second compartment of the carrier in advance of said one compartment and within the cabinet; means for unlocking said carrier following the liquid discharging operation; means for imparting sufficient rotational movement to the carrier upon unlocking same, 70 for the compartment thereof carrying the filled

cup, to be exposed in said delivery opening, and for a third compartment of the carrier to be disposed to receive a cup from the cup dispensing mechanism while the last deposited cup has been advanced by the carrier to a liquid-receiving position with respect to the liquid dispensing mechanism; means for relocking the carrier following its aforestated movement; said carrier walls having slots and vertical cam surfaces adapted to engage the upper portion of a cup resting on the carrier; and a fixed cam stop disposed in the path of movement of said slots and adapted to engage the lower portion of the cup, for co-action with said cam surfaces in response to the aforestated movement of the carrier, to roll from the exposed compartment of the carrier, any previously used cup replaced thereon, so as to prevent jamming of the carrier by such cup.

3. In a vending machine, a cabinet having a delivery opening; a carrier mounted in the cabinet for rotation about a vertical axis and divided into a plurality of compartments; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a second cup previously deposited in a compartment of the carrier in advance of said one compartment and within the cabinet; a movably mounted locking element having a locking lug; the carrier having locking recesses; means urging the locking element to a locking position wherein its locking lug will have locking engagement with one of said recesses; a reciprocably mounted actuating bar; means for reciprocating said bar; means on said bar co-acting with the locking element to move same to an unlocking position in a predetermined timed relationship to the cup filling operation; means on said bar and carrier co-acting to rotate the latter through a sufficient angular distance following the cup filling operation, for the filled cup to be exposed in said delivery opening; means by which said unlocking means is caused to release the locking element during the aforestated rotation of the carrier so as to render said urging means free to restore the locking element to locking position for relocking of the carrier when the aforestated rotation thereof is completed; and means co-acting with said carrier-rotating means to disrupt its operative connection to the carrier sufficiently prior to completion of the aforestated rotational movement of the carrier to compensate for its inertia and insure relocking of the carrier by said locking element.

4. In a vending machine, a cabinet having a delivery opening; a carrier mounted in the cabinet for rotation about a vertical axis and divided into a plurality of compartments; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a second cup previously deposited in a compartment of the carrier in advance of said one compartment and within the cabinet; a movably mounted locking element having a locking lug; the carrier having locking recesses; means urging the locking element to a locking position wherein its locking lug will have locking engagement with one of said recesses; a reciprocably mounted actuating bar; means on said bar co-acting with the locking element to

move same to an unlocking position in a predetermined timed relationship to the cup filling operation; a pawl mounted on said bar; means yieldingly urging said pawl to an active position; circumferentially spaced pins on said carrier, with one of which said pawl is adapted to co-act following the cup filling operation and unlocking of the carrier, to rotate the latter through a sufficient angular distance for the filled cup to be exposed in said delivery opening; said unlocking means releasing the locking element after the aforestated rotation of the carrier has been initiated, so as to render the first said urging means free to restore the locking element to locking position for relocking of the carrier when the aforestated rotation thereof has been completed.

5. In a vending machine, a cabinet having a delivery opening; a carrier mounted in the cabinet for rotation about a vertical axis and divided into a plurality of compartments; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a second cup previously deposited in a compartment of the carrier in advance of said one compartment and within the cabinet; a movably mounted locking element having a locking lug; the carrier having locking recesses; means urging the locking element to a locking position wherein its locking lug will have locking engagement with one of said recesses; a reciprocably mounted actuating bar; means for reciprocating said bar; means on said bar co-acting with the locking element to move same to an unlocking position in a predetermined timed relationship to the cup filling operation; a pawl mounted on said bar; means yieldingly urging said pawl to an active position; circumferentially spaced pins on said carrier, with one of which said pawl is adapted to co-act following the cup filling operation and unlocking of the carrier, to rotate the latter through a sufficient angular distance for the filled cup to be exposed in said delivery opening; means by which said unlocking means is caused to release the locking element after the aforestated rotation of the carrier has been initiated, so as to render the first said urging means free to restore the locking element to locking position for relocking of the carrier when the aforestated rotation thereof has been completed; and a fixed cam disposed to be engaged by and to move said pawl to an inactive position wherein it is disengaged from said one of the pins sufficiently prior to completion of the aforestated rotational movement of the carrier to compensate for its inertia and insure relocking of the carrier by said locking element.

6. In a vending machine, a cabinet having a delivery opening; a carrier mounted in the cabinet for rotation about a vertical axis and divided into a plurality of compartments; a cup dispensing mechanism; a liquid dispensing mechanism; means for actuating said cup dispensing mechanism to deposit a cup in one compartment of the carrier within the cabinet; means for actuating said liquid dispensing mechanism to discharge liquid into a cup previously deposited into a second compartment of the carrier in advance of said one compartment and within the cabinet; a movably mounted locking element having a locking lug; the carrier having locking recesses; means urging the locking element

11

to a locking position wherein its locking lug will have locking engagement with one of said recesses; a reciprocably mounted actuating bar; means for reciprocating said bar; means on said bar co-acting with the locking element during one stroke of said bar, to move the locking element to an unlocking position approximately when the cup filling operation has been completed; a pawl mounted on said bar; a spring urging the pawl to an active position; circumferentially spaced pins on said carrier which said pawl is adapted to pass idly during said one stroke of said bar, for engagement of the pawl with one of said pins during the return stroke of said bar, to effect rotation of the carrier through a sufficient angular distance following the cup filling operation, for the filled cup to be exposed in said delivery opening; means by which said unlocking means is caused to release the locking element after the aforestated rotation of the carrier has been effected, so as to render said urging means free to restore the locking element to locking position for relocking of the carrier when the aforestated rotation of the carrier has been completed.

7. In a vending machine, a turntable mounted for rotation about a vertical axis and having vertical walls dividing it circumferentially into a plurality of compartments; means for locking the turntable against rotation in a position wherein its compartments are respectively correlated with a loading station, a filling station, and a delivering station; a cup dispensing mechanism adapted to deposit a cup into that compartment of the turntable at the loading station; a liquid dispensing mechanism adapted to dispense liquid into a previously deposited cup in that compartment of the turntable at the filling station; means for actuating the locking means to unlock the turntable substantially upon completion of the filling operation; means operable following completion of the filling operation to rotate the turntable sufficiently to dispose the filled cup at the delivering station for removal of the cup from the turntable; and means for actuating the locking means to relock the turntable when the aforestated rotation thereof has been completed.

8. In a vending machine, a turntable mounted for rotation about a vertical axis and having vertical walls dividing it circumferentially into a plurality of compartments; means for locking the turntable against rotation in a position wherein its compartments are respectively correlated with a loading station, a filling station, and a delivering station; a cup dispensing mechanism adapted to deposit a cup into that compartment of the turntable at the loading station; a liquid dispensing mechanism adapted to dispense liquid into a previously deposited cup in that compartment of the turntable at the filling station; means for actuating the locking means to unlock the turntable substantially upon completion of the filling operation; means operable following completion of the filling operation, to rotate the turntable sufficiently to dispose the filled cup at the delivering station for removal of the cup from the turntable; means for actuating the locking means to relock the turntable when the aforestated rotation thereof has been completed; and means on the turntable and at the delivering station co-acting in response to said aforestated movement of the turntable, to move therefrom, any cup left or replaced in the compartment of the turntable at the delivering station, so as to prevent jamming of the turntable by such cup.

12

9. In a vending machine, a turntable mounted for rotation about a vertical axis and having vertical walls dividing it circumferentially into a plurality of compartments; means for locking the turntable against rotation in a position wherein its compartments are respectively correlated with a loading station, a filling station, and a delivering station; a cup dispensing mechanism adapted to deposit a cup into that compartment of the turntable at the loading station; a liquid dispensing mechanism adapted to dispense liquid into a previously deposited cup in that compartment of the turntable at the filling station; means for actuating the locking means to unlock the turntable substantially upon completion of the filling operation; means operable following completion of the filling operation, to rotate the turntable sufficiently to dispose the filled cup at the delivering station for removal of the cup from the turntable; means for actuating the locking means to relock the turntable when the aforestated rotation thereof has been completed; said walls having slots and vertical cam surfaces adapted to engage the side of a cup resting on the turntable; and a fixed cam stop adapted to pass through said slots and to engage the opposite side of a cup resting on the turntable, for co-action with any one of said cam surfaces in moving the cup from the turntable during rotation thereof, so as to prevent jamming of the machine by a used cup replaced on the turntable.

10. In a vending machine, a carrier; means mounting said carrier for rotation about a vertical axis with only a portion of the carrier accessible at a delivering station; means for locking the carrier against rotation with the other inaccessible portions of the carrier at loading and filling stations, respectively; means for dispensing a predetermined quantity of a fluid material into a cup on the carrier at said filling station; means for depositing a cup on the carrier at the loading station; means for actuating the locking means to unlock the carrier substantially at the completion of the cup filling operation; means for rotating the carrier through a partial revolution sufficiently to advance the deposited cup to the filling station and the filled cup to the delivering station; means for actuating the locking means to relock the carrier when moved as aforestated; and means controlling the carrier-rotating means to operatively disconnect same from the carrier sufficiently prior to completion of the aforestated carrier movement, to compensate for inertia of the carrier and insure relocking thereof at the completion of such movement.

11. In a vending machine, a carrier; means mounting said carrier for rotation about a vertical axis with only a portion of the carrier accessible at a delivering station; means for locking the carrier against rotation with the other inaccessible portions of the carrier at loading and filling stations, respectively; means for dispensing a predetermined quantity of a fluid material into a cup on the carrier at said filling station; means for depositing a cup on the carrier at the loading station; means for actuating the locking means to unlock the carrier substantially at the completion of the cup filling operation; means for rotating the carrier through a partial revolution sufficiently to advance the deposited cup to the filling station and the filled cup to the delivering station; means for actuating the locking means to relock the carrier when moved as aforestated; and means on the carrier and at the delivering station, operable in response to the aforestated

13

movement of the carrier, to move therefrom any previously used cup replaced thereon at the delivering station, so as to prevent jamming of the machine by such cup.

CHARLES J. WARREN.
